UNITED STATES PATENT OFFICE.

CELESTINE LEONTINE SCHMIT, OF MILWAUKEE, WISCONSIN.

DRAFTING INSTRUMENT.

1,200,035.

Specification of Letters Patent. Patented Oct. 3, 1916.

Application filed June 24, 1915. Serial No. 36,053.

To all whom it may concern:

Be it known that I, CELESTINE LEONTINE SCHMIT, a citizen of the United States, and resident of Milwaukee, in the county of Mil-

5 waukee and State of Wisconsin, have invented new and useful Improvements in Drafting Instruments, of which the following is a description, reference being had to the accompanying drawings, which are a

10 part of this specification.

This invention relates to improvements in drafting instruments more particularly adapted for use in the dressmaking art.

With the instruction of domestic art in 15 the school curriculum and the passing of laws which make this instruction obligatory for extension work in agricultural colleges and also in country agricultural schools, it has been found desirable to teach what is 20 known as the straight line method, which method is so much used in the governmental schools in France, Belgium, Switzerland and other European countries. This method is generally given as class instruction similar 25 to courses in mathematics and geometrical drawing but students not familiar with free hand drawing find difficulty in obtaining correct neck, arm and sleeve curves. Garments cut out too much around the neck or 30 arm openings are spoiled and if too tight necessitate additional fitting and cutting.

It is one of the objects of the present invention to overcome the before mentioned objectionable features and provide a drafting 35 instrument which may be conveniently used as a guide to mark on the material the correct curves for cutting the neck and arm openings and the sleeve curves.

A further object of the invention is to 40 provide a drafting instrument which may be used for marking and measuring both the right and left sides of the garment being made.

A further object of the invention is to 45 provide a drafting instrument which may be easily flexed or bent to conform to the contour of the portions of the garment being designed and made, thus eliminating the use of a tape.

50 A further object of the invention is to provide a drafting instrument which while particularly adapted for school use in teaching inexperienced scholars the art of dressmaking is also adapted for use by others 55 who are skilled in the dressmaking art.

A further object of the invention is to

provide a drafting instrument which is of very simple construction and is easily used and which may be manufactured and sold at a minimum cost.

With the above and other objects in view the invention consists of the improved drafting instrument and its parts and combinations as set forth in the claims, and all equivalents thereof.

In the accompanying drawing in which the same reference characters indicate the same parts in all of the views: Figure 1 is a side view of the improved drafting instrument; and Fig. 2 is a fragmentary portion 70 thereof showing one end portion flexed or folded to show the measuring scale on opposite sides of the instrument.

Referring to the drawing the numeral 5 indicates a sheet of flexible material of approximately triangular form. The back edge portion 6 and the shoulder edge portion 7 of the material are formed in straight lines disposed at right angles with relation to each other and the opposite sides of 80 the material adjacent the said edges have measuring scales 8 and 9 delineated thereon. The initial ends of the scales 8 and 9 start at the corner 10 of the straight line so that when the instrument is placed 85 against the back of the person being measured with the straight line 6 extending in a vertical direction and positioned centrally on the back of the person, the scale of the upper straight edge 7 will serve to 90 measure the distance from the center of the back to the arm opening on one side of the garment. Now by swinging the instrument over to the opposite side of the back and using the opposite side of the instrument the distance between the other arm opening and the center of the back and other measurements may be made. In 95 measuring curved portions of the garment the flexibility of the material permits the 100 scaled edge portions of the instrument being bent to the desired shape. The remaining edge 10 of the flexible sheet of material of the instrument is divided into three parts of which 11 is the neck opening curve, 12 the arm opening curve and 13 the sleeve curve. The neck and arm curves are of proper shape to serve as marking edges to mark approximately a one 105 quarter segment of each opening and are so proportioned as to serve for openings of 110 different diameter. As the openings increase

in diameter a greater length of each curved edge is used to outline the quarter segment of each opening.

The curved edge portions of the instrument are more particularly adapted for use as templets or guides in penciling in the outline of the openings upon paper or upon the cloth before cutting. The sleeve curve edge 13 is also used as a templet or 10 guide for marking the shape of the sleeve upon paper or upon the cloth before cutting.

In use in measuring and cutting a paper pattern or the material for the garment 15 the material is placed upon a flat surface and the instrument is then placed upon the material and used as a tri-square and measuring scale and the curved edge portions provide accurate templets for outlining the 20 curved edge portions of the garment being made.

While the drafting instrument has been described more particularly with relation to school work in teaching domestic art it 25 is to be understood that it is equally adaptable for use by experts in general dress-making and the claims are to be so construed.

From the foregoing description it will 30 be seen that the drafting instrument is of very simple construction and may be so cheaply manufactured and sold as to be placed within the reach of all of the pupils.

What I claim as my invention is:

35 1. A drafting instrument, comprising a piece of flat material having two straight

edge portions meeting to form a right angle and also having approximately a hypotenuse edge portion which extends from the outer end of one straight edge portion to 40 the other in a series of curves to form a templet for outlining the neck and arm openings and the curve of a sleeve of a dress, said sleeve curve positioned intermediate of the other curved portions, portions 45 of the material adjacent the straight edges having scales delineated thereon.

2. A drafting instrument, comprising a piece of flat flexible material having two straight edge portions meeting to form a 50 right angle and also having approximately a hypotenuse edge portion which extends from the outer end of one straight edge portion to the other in a series of curves to form a templet for outlining the neck 55 and arm openings and the curve of a sleeve of a dress, said neck and arm opening curves positioned adjacent the outer ends of the straight edge portions and forming approximately one quarter segment of each 60 opening and being shaped to serve for openings of different diameters, and the sleeve curve edge portion positioned intermediate the neck and arm curved edge portions, the opposite sides of the material adjacent the 65 straight edges having measuring scales delineated thereon which start from the point of junction of the two straight edge portions.

In testimony whereof, I affix my signature.

CELESTINE LEONTINE SCHMIT.
